UNITED STATES PATENT OFFICE.

SELLERT ALLEMAN, OF SWARTHMORE, PENNSYLVANIA, ASSIGNOR TO SUN OIL COMPANY, OF PHILADELPHIA, PENNSYLVANIA, A CORPORATION OF NEW JERSEY.

SHEEP DIP.

No Drawing.

Application filed March 24, 1923. Serial No. 627,313.

My invention is a new and useful composition intended principally for use as a "sheep dip" but adaptable to other uses. The wool of sheep becomes infected with 5 various vermin and insects, such as ticks, lice, fleas and jiggers, as well as harmful germs, and while there are known antisepsics that are more or less efficacious, they are expensive, or their action is not thorough, or the effects are transitory, or they 10 are more or less poisonous to the sheep especially if taken internally.

The primary object of my invention is to provide a sheep dip that will be inexpensive 15 to manufacture, that will not be uneconomical even if applied in liberal quantities, that will act upon every hair of the wool from the root to the tip, that will be harmless to the sheep even if more or less of the composition is swallowed, and that will have 20 effects so lasting as to make frequent applications unnecessary.

I use as the principal ingredient of my composition a substance which is not only 25 readily available but is deemed of so little value that it is often allowed to go to waste. In the refining of mineral oils, it is customary to treat the stock in an agitator, first with a mineral acid and then with an alkali, 30 usually caustic soda, leaving a residue variously known as soda residue, alkali precipitate, etc. This residue, particularly where the stock treated is lubricating oil stock, is a mixture or emulsion of fatty acid soaps, 35 mineral lubricating oil and alkaline salt water. As drawn from the agitator, a typical composition would be: fatty acid soap, ten or twelve parts; mineral oil, twenty-eight or thirty parts; and alkaline salt water, 40 including some free alkali, sixty parts. It is desirable to allow this mixture to settle, and then draw off the lower layer of alkaline salt water. The proportions of fatty acid soap, mineral oil and alkaline salt 45 water in the mixture that is drawn from the agitator will, of course, vary with different crude petroleums and with different refinery practices. After the lower layer of alkaline salt water is drawn off, a typical 50 composition would be: fatty acid soap,

twenty-two per cent.; mineral oil, fifty-five per cent.; water, twenty-three per cent. It is this substance which I have practically used as the main ingredient of my composition, although it will be understood that the 55 relative proportions of fatty acid soap and mineral oil may be varied within a rather wide range, while the percentage of water (by reason of the dilution of the composition before use) is immaterial. While fatty acid soap is specified as one of the ingredients of this soda sludge, it is known that a substantial proportion of this ingredient (say sixty per cent) is composed of resins similar to fossil resins, the remainder only 60 being, strictly defined, a true (sodium) soap.

This emulsion of fatty acid soap and mineral oil may be manufactured in other ways. Thus the alkali precipitate above mentioned 65 may be treated with a weak solution of a mineral acid (say seven per cent sulfuric acid), thereby decomposing the soap. Upon settlement it divides into an upper layer of fatty acids and mineral oil and a bottom 70 layer of salt water, which may be drawn off. This process is set forth in the Maitland Patents No. 1,425,882 and No. 1,425,884, issued August 15, 1922. These fatty acids, or, as they are also termed, organic acids or saponifiable oils, are water-insoluble and 75 readily saponifiable. When saponified, they are miscible in all proportions with water and mineral oil. Instead of the unpurified alkali precipitate above mentioned, I may utilize a saponified fatty acid of this character, provided, however, that a substantial proportion of lubricating or other mineral oil is not separated out therefrom or (if largely or wholly separated out) is afterward added thereto; a saponified fatty acid, 80 whether derived from animal, vegetable or mineral sources, unmixed with a large proportion of mineral oil, being inoperative to 85 secure the results obtained by the use of my composition. It may be added that this described purified fatty acid soap has no superior utility for my purpose over the previously described alkali precipitate, which latter, being cheaper, is used preferably. 90 The only advantage of utilizing the purified 95 100

fatty acid soaps is that practically all free alkali is eliminated therefrom, thereby eliminating a more or less objectionable ingredient and reducing the bulk of the product by 5 reason of the removal of most of the water, the latter factor involving a saving in freight. So far, however, as the free alkali may be objectionable, it is neutralized in my finished product by the addition of acid, as 10 hereinafter explained.

Fatty acid soaps are derivable from mineral oil by other methods, but these it is unnecessary to describe, as I have hereinbefore described two methods, and the method 15 of extracting them is not material.

To the alkali precipitate, or other solution or colloidal suspension of fatty acids, and mineral oil, I add one of the tar acids, preferably cresylic acid (composed of a mixture of ortho, meta and para cresols),

Other tar acids, particularly carbolic acid, 25 $\text{C}_6\text{H}_5\text{OH}$, are usable, but have less desirable properties than cresylic acid.

A mixture of tar acids may also be used. In practicing the process with the alkali precipitate that I have used, which is a derivative 30 of asphaltic or naphthenic crude petroleum (specifically Texas crude), I proceed by adding the cresylic acid to the alkali precipitate until the yellow alkali precipitate loses its taffy-like consistency and appearance 35 and attains the consistency and appearance of ordinary oil. The proportions that I have found practicable to add vary from about ten per cent to about thirty per cent of the composition after such addition. 40 Seven per cent I have found to be too small a proportion to secure the consistency and appearance sought, while the excess over substantially more than thirty per cent will not combine with, or dissolve in, the alkali precipitate. I prefer to add the largest 45 specified proportion of cresylic acid, or about thirty per cent. If, however, the mixture of petroleum-derived fatty acid soap and mineral oil is something other than the impure alkali precipitate which I 50 preferably use, or if such alkali precipitate is derived from other crude petroleum than that above specified, the permissible range of proportions of cresylic acid may differ 55 from that above specified.

I am uncertain whether the product resulting from the above additions of cresylic acid is a solution or a compound formed by the union of the substances. The two substances will not separate on long standing, even in cold weather.

It is not required that the tar acids should be added in a pure state. There are certain so-called tars, containing tar acids, that 60 65 can be substituted for the tar acids; al-

though, of course, the proportion of the substituted ingredient would vary with its content of tar acid. Distillates from such tars are also available. As examples of such substances may be mentioned Scotch 70 blast furnace oil, lignite tar (produced in the Ruhr district of Germany) and tars from low temperature carbonization of coal. Any of these tars, or their distillates, are 75 usable.

My new composition is soluble, or miscible, or emulsifiable, in all proportions, in water. It possesses remarkable antiseptic and other desirable properties.

When used as a sheep dip, for which it 80 is more especially intended, it is dissolved (say) in about 200 parts of water. The animal may be sprayed or washed with the composition, but where a large flock of sheep is to be treated, it is practicable and 85 desirable to run the composition into a large vat and drive the sheep through the vat, the bath being deep enough to almost or quite submerge the trunk of the sheep. All 90 vermin, insects, and germs are destroyed. In addition to the value of the composition in this regard, the hair of the animal is rendered soft. The composition is also an excellent detergent.

Cresylic acid is a known antiseptic, but 95 its use as a sheep dip or animal cleaner, when merely dissolved in water, is objectionable. When so added it rapidly volatilizes and therefore has no subsequent protective effect. Moreover, its use is dangerous, as it is more or less poisonous when swallowed. Again, it does not thoroughly act upon the entire mass of hair. My new composition, after evaporation of water, remains on the sheep for a long time after 100 treatment, and it has no poisonous action if swallowed. The globules of the composition actually climb the hair from root to top and therefore the action is extremely 105 thorough.

It is not necessary to treat the sheep with 110 my new composition with frequency, as the composition acts protectively for months after administration. It is not absolutely necessary to dip the sheep oftener than once a year, although one treatment every three months is advisable. If the sheep are treated once every three months, or thereabouts, as much as 250 parts of water to one part of the composition may be added. If treated every six months, the composition should be applied in less dilute form, say 200 parts of water; while if treated 115 annually, only 150 parts of water may be added. These proportions seem to be desirable based upon observation, experiment and practical use, but use of the composition on a more extensive and prolonged scale may make it desirable to modify the degrees of dilution above recommended. If 120 125 130

a solution, or a colloidal suspension, of petroleum-derived fatty acid and mineral oil is used from which the water has been largely or wholly eliminated, a correspondingly greater dilution would be desirable; while if it contains a larger percentage of water than that herein specified, the degree of dilution with water would be reduced.

In my new composition, the alkali precipitate itself has valuable antiseptic properties, and therefore it may be used to supplement the action of any known animal antiseptic provided that, when dissolved in or combined therewith, it does not form an electrolyte.

It should be understood that the fatty acid soap herein described as an ingredient of my improved composition has necessarily the characteristics of the fatty acid soap contained in the alkali precipitate resulting from the treatment with an alkali of acid-treated mineral lubricating stock, as hereinbefore described, and does not have the characteristics of saponified sulfonic acids. Sulfonic acids, while derived from mineral oil, are water-soluble and contain a high percentage, usually about sixteen per cent of combined sulfur, and are not, it is believed, fatty acids, which are water insoluble (before saponification) and contain no combined sulfur, although they may have a small percentage of sulfates as impurities, and which are preferably removable, as herein described. It should be understood, therefore, that in specifying, in the claims, a fatty acid soap derivative from mineral oil, the term is not apt to include, and is distinctly intended to exclude, sulfonic acids or naphthenic acids, neither of which could be substituted for the fatty acid soap derivative described.

While, as above stated, my new composition is intended primarily for use as a sheep dip, it is adapted for use as an antiseptic in treating other animals than sheep. It is also adapted for use as a plant and tree spray.

I am aware that oleic acid soap is known as an antiseptic and that it has been rendered fluid by adding carbolic acid or cresylic acid so as to give a finished product containing about thirty-six per cent of such acid. Applicant's emulsion of fatty acid soap and mineral oil possesses sufficient fluidity without the addition of cresylic acid, which is added thereto solely to increase the antiseptic properties. This old composition is harsh and irritating to the skin and, because of its high surface tension, does not spread over the skin or hair. My composition not only involves the use of the saponified derivative from petroleum hereinbefore described, but the emulsion therewith of a substantially larger proportion of mineral oil (preferably lubricating oil). While the preferred percentage of cresylic acid in my

finished product is somewhat smaller than in this old composition, the percentage in my composition of cresylic acid to the so-called "saponified fatty acid" is much greater than in the old composition—being 70 in fact preferably in larger proportion than such "saponified fatty acid" and always in much larger proportion than that constituent thereof which is a true sodium soap.

Having now fully described by invention, 75 what I claim and desire to protect by Letters Patent is:—

1. A new composition adapted for use in dilute form as a sheep dip and plant and tree spray, comprising mineral oil, a fatty acid soap derivative from mineral oil, and cresylic acid. 80

2. A new composition adapted for use in dilute form as a sheep dip and plant and tree spray, comprising mineral oil, a fatty acid soap derivative from mineral oil, and a tar acid. 85

3. A new composition adapted for use in dilute form as a sheep dip and plant and tree spray, comprising mineral oil and a fatty acid soap derivative from mineral oil, and an antiseptic which when added thereto does not form an electrolyte. 90

4. A new composition adapted for use as a sheep dip and tree spray, comprising mineral oil, a fatty acid soap derivative from mineral oil, a tar acid, and substantially over one hundred parts of water to one part of the other ingredients. 95

5. A new composition adapted for use in dilute form as a sheep dip and plant and tree spray, comprising mineral oil, a fatty acid soap derivative from mineral oil, and a tar acid, the proportion of mineral oil being substantially in excess of the proportion of 100 said fatty acid soap derivative. 105

6. A new composition adapted for use in dilute form as a sheep dip and plant and tree spray, comprising mineral oil, a fatty acid soap derivative from mineral oil, and an antiseptic which added thereto does not form 110 an electrolyte, the percentage of mineral oil being in excess of that of either of the other ingredients.

7. A new composition adapted for use in dilute form as a sheep dip and plant and tree spray, comprising mineral oil, a fatty acid soap derivative from mineral oil and a tar acid, the tar acid being in not substantially 115 smaller proportion than the fatty acid soap derivative. 120

8. A new composition adapted for use in dilute form as a sheep dip and plant and tree spray, comprising a fatty acid soap derivative from mineral oil, a tar acid in not substantially smaller proportion than the fatty acid soap derivative, and mineral oil in larger proportion than either of the other two ingredients. 125

9. A new composition adapted for use in 130

dilute form as a sheep dip and plant and tree spray, comprising mineral oil, a fatty acid soap derivative from mineral oil, petroleum resins, and a tar acid.

5 10. A new composition adapted for use in dilute form as a sheep dip and plant and tree spray, comprising a fatty acid soap derivative from mineral oil, petroleum resins, a tar

acid in not substantially smaller proportion than said soap derivative, and mineral oil ¹⁰ in substantially larger proportion than said soap derivative.

In testimony of which invention, I have hereunto set my hand, at Swarthmore, Penna., on this 13th day of March, 1923.

GELLERT ALLEMAN.
